Primary Examiner — George D. Kirschbaum*Assistant Examiner* — Maria J. Edwards(74) *Attorney, Agent, or Firm* — Polsinelli PC(57) **CLAIM**

We claim the ornamental design for an infant swaddle device, as shown and described.

DESCRIPTION

FIG. 1 is a top isometric view of an infant swaddle device, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines depict portions of the infant swaddle device which form no part of the claimed design.

1 Claim, 3 Drawing Sheets---
